CURVILINEAR COLLAR LINER

John V. Moore, Pawtucket, R. I., assignor to Moore
Fabric Company, Pawtucket, R. I., a corpora-
tion of Rhode Island

Application March 19, 1940, Serial No. 324,768

2 Claims. (Cl. 139—385.5)

This invention relates to the manufacture of collars for men's wear, either of attached or detached type.

It is the general object of my invention to provide a liner for such collars so constructed that it will assume a definite curvilinear form on shrinking and finishing, and that it will thereafter permanently retain such curvilinear form.

A further object of the invention is to provide 10 a curvilinear collar liner of such construction that it may be woven as a straight flat fabric which does not assume curvilinear form until removed from the loom and subjected to shrinking and finishing operations.

15 My invention further relates to arrangements and combinations of parts which will be herein-after described and more particularly pointed out in the appended claims.

A preferred form of the invention is shown in 20 the drawing, in which

Fig. 1 is a plan view of a portion of my improved collar liner, as woven;

Fig. 2 is a similar view of a portion of the liner after shrinking and finishing;

25 Fig. 3 is a front view of a conical warp beam preferably used for the binder threads; and

Fig. 4 is a front view of a graduated reed.

Referring to the drawing, my improved collar liner is woven as a straight flat continuous fabric 30 having a body portion 10 and a fold portion 11. The body portion 10 is of multi-ply construction, while the fold portion 11 is made single-ply and using relatively light warp threads only.

In the body portion 10, I provide a set of 35 face warp threads 12 of relatively larger diameter and softer finish, and a second set of binder warp threads 14 which are of relatively smaller diameter and harder finish. The weft threads 16 commonly correspond more or less in size and 40 finish to the binder warp threads 14. In the fold portion 11, warp threads 18 only are used and these threads more or less correspond to the binder warps 14 in size.

The fabric is preferably woven in a graduated 45 reed of the type shown at 20 in Fig. 4, in which the spacing of the reed dents increases progressively from one side of the reed to the other. The more finely graduated side of the reed corresponds to the side S of the woven fabric, so 50 that the warp threads 12 and 14 are thus crowded more closely together in the part S.

I also find it desirable to wind the binder warp threads 14 on a tapered warp beam, as shown at 22 in Fig. 3, and this warp beam is so disposed during weaving that the small end of the

beam will be at the side S of the fabric, at which side also the warp threads are crowded more closely together.

It will thus be evident that, as the cloth is woven, a slightly greater length of binder warps 5 14 will be fed to the cloth at the side S' of the fabric, where the warp threads 12 and 14 are also more widely spaced. The side S of the fabric is thus of greater density and more tightly woven, first from having a greater number of 10 warp threads per unit of width, and second from having the binder warps therein under greater tension during the weaving.

When the straight fabric thus woven is removed from the loom and subjected to shrinking 15 and finishing operations, the side S of the fabric, being more closely and also more tightly woven, will resist shrinkage, while the side S', being more coarsely and less tightly woven, will shrink quite readily. Consequently, the collar 20 liner on shrinking will assume the curvilinear shape shown in Fig. 2, with the convex or outer portion 30 corresponding to the portion S of the straight fabric and with the concave portion 31 corresponding to the portion S'.

25 As previously explained, the fine end of the reed 20 and the small end of the warp beam 22 are associated in producing the portion S which becomes the long or convex edge of the finished fabric.

I thus produce a curvilinear collar liner having an easily flexible fold portion along its concave edge, which fabric may be easily and rapidly woven straight in an ordinary loom but which assumes a natural and permanent curvature 35 when subjected to shrinking and finishing operations.

The amount of curvature can be varied by 40 varying the spacing of the graduated reed 20 and also by varying the taper of the warp beam 40 22. For ordinary purposes, it is not necessary to vary the size of the warps 12 or 14 across the face of the fabric, but warps of increased size might be used in the portion S where excessive curvature is required.

45 It is to be particularly noted that the curvature on shrinkage is due to the greater density and firmer weaving tension of the portion S of the fabric, which portion resists shrinkage more effectively than the loosely and slackly woven portion S'.

Having thus described my invention and the advantages thereof, I do not wish to be limited to the details herein disclosed, otherwise than as set forth in the claims, but what I claim is, 55

1. A curvilinear collar liner having a multi-ply body portion with a narrow single-ply fold portion disposed at one edge thereof, said body portion comprising weft threads, face warps, and binder warps, with the spacing of the warp threads gradually increasing toward said fold portion and with the tension of the binder warps gradually decreasing toward said fold portion, all parts of said liner being so constructed and arranged that said liner is substantially straight as woven but assumes a predetermined curvilinear shape on shrinkage, with said fold portion disposed at the shorter and concave edge.

2. A curvilinear collar liner having a multi-

ply body portion with a narrow single-ply fold portion disposed at one edge thereof, said body portion comprising non-elastic weft threads and non-elastic warp threads, with the spacing of the warp threads gradually increasing toward said fold portion and with the tension of certain of the warp threads gradually decreasing toward said fold portion, all parts of said liner being so constructed and arranged that said liner is substantially straight as woven but assumes a predetermined curvilinear shape on shrinkage, with said fold portion at the shorter and concave edge.

JOHN V. MOORE.
